US00D977502S

(12) **United States Design Patent** (10) Patent No.: **US D977,502 S**
Lu et al. (45) Date of Patent: **** Feb. 7, 2023**

- (54) **DISPLAY SCREEN WITH GRAPHICAL USER INTERFACE**
- (71) Applicant: **Insulet Corporation**, Acton, MA (US)
- (72) Inventors: **Virginia Lu**, Fairfax, VA (US); **Gonzalo Castro**, Harvard, MA (US); **Graeme Nelson**, Oakland, CA (US); **Joshua Siva**, San Diego, CA (US); **Megan Zwerling**, San Diego, CA (US); **Scott Martin**, San Diego, CA (US)
- (73) Assignee: **INSULET CORPORATION**, Acton, MA (US)
- (**) Term: **15 Years**
- (21) Appl. No.: **29/737,480**
- (22) Filed: **Jun. 9, 2020**
- (51) LOC (14) Cl. **14-04**
- (52) U.S. Cl. **D14/486; D14/488**
- (58) **Field of Classification Search**
USPC D14/485-495
CPC G06F 3/048-04897
See application file for complete search history.

(57)

CLAIM

The ornamental design for a display screen with graphical user interface, as shown and described.

DESCRIPTION

The FIGURE is a front view of a display screen with a graphical user interface showing our new design.

The broken lines showing a display screen, text, and graphical elements form no part of the claimed design.
